(57) **CLAIM**

The ornamental design for a hose, as shown and described.

DESCRIPTION

FIG. 1 is a first perspective view of a hose showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is an enlarged top view thereof;

FIG. 8 is an enlarged bottom view thereof;

FIG. 9 is an enlarged view of the selected portion 9 in FIG. 1; and,

FIG. 10 is an enlarged view of the selected portion 10 in FIG. 1.

The broken lines shown in the drawings depict portions of the hose that form no part of the claimed design.

1 Claim, 10 Drawing Sheets
